UNITED STATES PATENT OFFICE.

HARRY J. MOREY, OF SYRACUSE, NEW YORK, ASSIGNOR TO PASS & SEYMOUR, INC., OF SOLVAY, NEW YORK, A CORPORATION OF NEW YORK.

ELECTRIC FIXTURE-SWITCH.

1,295,563.

Specification of Letters Patent. Patented Feb. 25, 1919.

Application filed March 7, 1916. Serial No. 82,678.

To all whom it may concern:

Be it known that I, HARRY J. MOREY, a citizen of the United States, residing at Syracuse, Onondaga county, State of New York, have invented certain new and useful Improvements in Electric Fixture-Switches, of which the following is a specification.

My invention relates to electric switches and has particular reference to improvements in pull fixture switches such as are supported on ceilings to suspend fixtures or incandescent lamps.

The object of the invention is to generally improve devices of the above character so that the switching mechanism may be used for heavy currents.

Another object of the invention is to design a switch of this type which may be attached to an ordinary outlet box and serve as a cover therefor, and to provide a device which may be readily wired from the front of the box.

The above and other objects and the novel features of my invention will be apparent from the following description taken in connection with the drawing in which,

Figure 1 is a side elevation showing a fixture switch embodying my invention secured in place on a ceiling;

Fig. 2 is a plan view of the same with the cover removed;

Fig. 3 is a plan view of the base of the supporting body and showing the cap part removed therefrom and in bottom plan view;

Fig. 4 is a detail view showing the cavity in the block and the parts fixed in the cavity;

Fig. 5 is a detail plan view of the switch member and ratchet disk in the cavity of the insulating base;

Fig. 6 is a cross sectional view of the switch taken on the line 6—6 of Fig. 2;

Fig. 7 is a cross sectional view of the switch at right angles to the section of Fig. 6 and taken on the line 7—7 of Fig. 2; and

Fig. 8 is a dropped perspective view of the switch member and associated parts.

Referring to the drawing, the supporting body for the switch comprises a base member 10 and a cap member 11, both of which are of insulating material such as porcelain. The base member 10 is circular in outline and is adapted to serve as a cover for an outlet box, such as the box 12, shown in Fig. 1,

the holes 13 in the base 10 serving to receive screws by means of which the base is secured to the flange at the open end of the outlet box. The base member 10 is provided with a central cavity 14 which is provided with a transversely extending second cavity or depression 15. The base 10 also has two openings 16 on opposite sides of the cavity 14 and extending through the base. Between the central cavity 14 and the cavities 16 there are projections 17 upon which the terminal plates 18 are mounted. The terminal plates 18 are secured to the base by the screws 181 and are provided with binding screws 19. The terminal plates 18 also have parts 20 which extend into the cavity 14 and serve as switch contact faces. The line wires 21 may be drawn from the outlet box through the openings 16 and hooked over the projections 17 and plates 18 from the front of the base 10. The cap part 11 is provided with recesses 111 on opposite sides thereof which register with the binding screws 19 so that the latter may be turned when the cap is secured in place on the base. The cap 11 is mounted in contact with the rests 112 which surround the cavity 14 on the base.

The bottom of the transverse cavity 15 has a pair of flat steel springs 22 therein, the springs resting at their edges on the bottom of the cavity. The opposite ends of the springs are secured to the base 10 by means of the plates 24 and the screws 25. The springs 22 are spaced apart and at the center an angular snapping cam 26 is held between them. The snapping cam is shown in perspective in Fig. 8 and consists of a single piece of metal which has a square base part 27 and two upturned ends 28. The upturned ends are provided with pairs of shoulders 29 and 30 to form sections 31 and 32, respectively, on those ends of different heights, for a purpose to be described. The base 27 of the cam member 26 has a central opening 100 to receive the spindle 33 which is set upright in a socket in the bottom of the depression 15.

The spindle 33 also extends through the opening 34 at the center of an insulating disk 35 which carries the elongated arcuate conductors 36 on opposite sides thereof. The disk 35 and conductors thereon constitute the switch member of the device. The construction of the switch member will be clear 110

from an inspection of Fig. 8. On opposite sides of the center the disk 35 has pairs of radial slots 37, 38, the slot 37 opening to the periphery of the disk. The conducting member 36 consists of a single strip of copper which is wound through the slots 37 and 38 and bent so as to fit against the flat faces of the disk 35. The closed slot 38 will keep the strip from slipping off the disk. In this manner a switch member is provided which has conductors on both faces thereof which are electrically connected together and extend from one face to the opposite face of the switch member. 15 Near the center on opposite sides of the opening 34 the disk 35 has rectangular slots 39 of sufficient length to pass over the reduced portions 31 at the ends of the cam member 26 and are arranged to rest on the shoulders 29. This forms a rigid connection between the cam member and the switch member so that these two parts will move together when the cam is rotated. 20 The means for rotating the cam member 25 consists of a ratchet disk 40 and a ratchet lever 41. The ratchet disk 40 is provided at its periphery with the four notches 42 spaced equal distances apart around the edge of the disk. At its center the disk 40 30 has a hole 43 to fit the spindle 33 and on opposite sides of the hole 43 are shorter rectangular slots 44 adapted to fit the narrow portions 32 at opposite ends of the cam member 26. The slots 44 are of substantially the same length as the width of the parts 32 of the cam and the disk 40 will therefore rest on the shoulders 30 and above the insulating disk 35. The ratchet lever 41 35 consists of a substantially central part 45 and an arm 46 integrally connected therewith, the arm terminating at the outer end in a lug 47, provided with a slot and opening 48 to receive the end ball of a chain or cord 49, by means of which the lever is 40 operated. At the center of the part 45 the lever 41 has an opening 50 which fits the spindle 33. At the outer edge of the part 45 there is an integral lug 51 which is 45 adapted to engage any one of the notches 42 in the edge of the disk 40 to rotate the latter. The spindle carries a sleeve 52 at its upper end provided with a head 53. The upper side of the head 53 is provided with a transverse slot 54 and also has openings 55 50 therethrough for receiving the end 56 of the spring 57, which is wound spirally around the sleeve 52 and the spindle 33. The opposite end 58 of the spring is hooked and engages a hook 59 struck from the part 55 of the operating lever 41. The spring, when properly tensioned, is designed to restore the operating lever to its normal position and cause the lug 51 to engage in the next notch 42 to the rear of the one disengaged. 60

The cap part 11 is provided with a central opening 60 and around the inner edge of the opening 60 there is a square shoulder 61 to receive the head 53 and prevent it from turning. The cap part 11 is secured to the base part 10 by the screws 62 passing through the openings 621 and when so secured in place the head 53 may be engaged through the opening 60 and turned to sufficiently tension the spring 57. 75

The inner side of the cap part 11 has the spring fingers 63 secured thereto by screws 64 which pass through one end of the fingers 63, the opposite ends 65 of the fingers being bent away from the face of the cap 80 and having a sufficient degree of resiliency to engage the conductors 36 of the switch member. The secured ends of the fingers are set in grooves 66 in the face of the cap member 11. The screws 64 pass through the body of the cap member 11 and the outer ends thereof engage the branch terminal plates 67 and hold them in position in recesses 68 in the outer face of the cap. The branch terminal plates 67 are provided with 90 binding screws 69 by means of which the lamp cord or branch circuit wires may be electrically connected to the plates 67. The cap member 11 is provided at opposite sides thereof with integral hooks 70, the grooves 95 71 of which face toward the base 10. The hooks 70 are provided so that the cord connected to the branch terminal plates 67 may be wound over them to relieve the strain and prevent it from breaking the connection at 100 the binding screws.

The operating cord 49 is guided by a groove 74 in the outer face of the base 10 and the chain cord passes through a guide funnel 75 secured by a screw 76 to the base 10 adjacent the outer end of the groove 74. The front face of the device is inclosed by a bell shaped metal shell 77 which is provided on opposite sides with holes to receive the buttons 78 on spring fingers 79 secured to the base 10 on opposite sides of its center. The buttons 78 are depressible and when it is desired to remove the shell 77 they are disengaged by pressing them inwardly and pulling down on the shell. In order to replace the shell it is only necessary to register the buttons 78 with the openings in the shell and press upwardly until the buttons snap into place. The shell will then be supported from the base 10 by the springs 79 and buttons 78. The shell 77 has an opening at the bottom through which the branch circuit wires 80 depend. 110 115 120

The operation of the switch will be apparent from the foregoing description. The switch member, comprising the disk 35 and the conductors carried by it, is located in the cavity and between pairs of contacts 20 and 65, which latter are disposed opposite each other on opposite sides of the center of 125 130

the base. When the disk 40 has been rotated a quarter of a revolution by a pull on the lever 41 the cam member 26 is turned and will spread the springs 22 apart and near the end of the stroke of the lever 41 the cam member 26 will pass a point mid-way between the off and on positions of the switch, at which point the diagonal corners of the cam 26 will move rapidly along the inner faces of the springs 22 and the cam will be suddenly snapped to the next position, carrying with it the switch member and the ratchet disk. This sudden movement of the switch member is an important feature as it makes and breaks the circuit with a snap and prevents injurious arcing at the contacts. When the cord connected to the lever 41 is released the spring 57 restores it to its normal position. At the off position of the switch the insulating disk 23 is interposed between the switch contacts provided by the portions 20 of the terminal plates on the base and the switch contacts provided by the ends 65 of the fingers on the cap piece 11. While I have shown and described the construction in detail I do not wish to be limited to the exact form disclosed as it will be clear that various changes may be resorted to without departing from the spirit of the invention.

Having thus described the invention, what is claimed and desired to be secured by Letters Patent is:

1. In an electric switch, the combination of a support comprising two blocks of insulating material secured together and having a space between them, line terminals on one of said blocks, circuit terminals on the other block, a switch member comprising an insulating disk carrying conductors for connecting the line terminals with the circuit terminals, and means for operating said switch member comprising means for intermittently imparting to the switch member a partial turn and means for snapping the switch member before the end of each partial turn.
2. In an electric switch, the combination of a base of insulating material having a central cavity and openings completely surrounded by the insulating material and extending through the base on opposite sides of the central cavity, through which openings the line wires are accessible from the front of the base, line terminals provided with securing screws and located between said openings and cavity and having portions extending into the cavity to serve as switch contact faces, a cap member of insulating material secured to said base and closing the cavity therein but not covering the openings nor the screws of the line terminals, switch contact faces on said cap extending into the space between the cap and base, branch circuit terminals on the cap connected to the
3. In an electric switch, the combination of a base of insulating material having a central cavity in one face thereof and openings extending through the base on opposite sides of the central cavity through which the line wires are accessible from the front of the base, line terminals having securing screws disposed adjacent the openings through the base, said line terminals also having portions projecting into the cavity, branch circuit terminals, and means for electrically connecting the line terminals to the branch circuit terminals comprising a switch member in said cavity, means for rotating said switch member, and means in said cavity for imparting a sudden action to the switch member.
4. In an electric switch, the combination of a base of insulating material having a central cavity, completely surrounded by the insulating material, and openings for line wires extending through the base on opposite sides of the cavity, line terminals attached to the base on opposite sides of said cavity adjacent said openings, said line terminals being provided with portions forming contact faces extending into the cavity, branch circuit terminals, and means for electrically connecting the line terminals to the branch circuit terminals comprising a switch member in the cavity, a switch lever for operating said switch member extending from the cavity, and a ball chain attached to said lever, said base having a groove along the outer edge thereof to guide said chain.
5. In an electric switch, the combination of an insulating base having a central cavity and line terminals at opposite sides of said cavity, said terminals being provided with securing screws and having parts projecting into the cavity to form switch contact faces therein, a pair of spaced curved springs secured in the bottom of said cavity, a spindle mounted at the center of said cavity, an angular cam member mounted on said spindle and located between said springs, a switch member secured to said cam member, a ratchet disk secured to the cam member, and a ratchet lever for rotating the ratchet disk.
6. In a device of the class described, the combination of a base of insulating material constituting an outlet box cover and having a cavity in the outer face thereof, said base also having openings therethrough at the sides of said cavity, permitting access to the line wires from the front of the base, line terminals on said base adjacent said openings and provided with portions extending

4

into said cavity to form switch contact faces, branch circuit terminals, and means for electrically connecting the branch circuit terminals with the line terminals comprising a 5 switch member in said cavity having conductors adapted to engage the switch contact faces on the line terminals, and means for rotating said switch member.

7. In an electric switch, the combination 10 of a base having a cavity therein, a pair of springs secured in the bottom of the cavity and spaced apart intermediate their ends, a spindle mounted in the cavity, a cam member carried by the spindle and located between the springs, said cam member having ends provided with shoulders at different heights from the bottom of the cavity, a 15 switch member having a recess to fit the spindle and adapted to be supported on the lower shoulders of the cam member, a ratchet disk having a recess fitting the spindle and supported on the shoulders above the switch member, and a lever fitting the spindle and adapted to rotate the ratchet 20 disk, cam member and switch member.

8. In an electric switch, the combination 25 of a base of insulating material having a cavity, switch contact faces in said cavity having terminals, spring plates secured at opposite ends in the bottom of said cavity, a vertical spindle at the center of said cavity, an angular cam member between said 30 springs and mounted on said spindle, said cam member comprising a plate having upwardly bent ends, said upwardly bent ends being narrower at the top than at the base, a switch member having contact faces adapted 35 to engage the switch contact faces on the base, and being provided with openings to 40 receive the spindle and the upwardly bent ends of the cam member, a ratchet disk hav-

ing openings adapted to receive the spindle and the upwardly bent ends of the cam member, and an operating lever mounted on said spindle for rotating said ratchet disk.

9. In an electric switch, the combination 45 of a support comprising two blocks of insulating material secured together and having a space between them, line terminals and circuit terminals on said support, a switch 50 contact on each of said blocks extending into the space between the blocks, a switch member comprising an insulating disk carrying elongated electrically connected conductors on opposite sides thereof, and means for operating the switch member comprising snapping mechanism to suddenly make and break the circuit between said contacts, the length of said conductors being such that the disk may be rotated for a limited distance without 55 breaking the circuit between said contacts before the snapping mechanism acts.

10. A switch member comprising a circular insulating disk having two pairs of spaced substantially radial slots, and a strip 60 of conducting material having parts thereof fitting against the opposite faces of the disk between the members of each pair of slots and having a portion thereof extending through one of the slots to hold said strip 65 in place.

11. A switch member comprising a circular disk of insulating material having formed therein two pairs of spaced, substantially radial slots, one member of each pair 70 opening through the periphery of the disk, and a strip of conducting material wound over both faces of the disk between the members of each pair of slots, for the purpose described.

In testimony whereof I affix my signature.
HARRY J. MOREY.
